UNITED STATES PATENT OFFICE.

LOUIS J. CHANDLER, OF SPRINGFIELD, MASSACHUSETTS.

DESIGN FOR A BADGE.

SPECIFICATION forming part of Design No. 22,528, dated June 13, 1893.

Application filed March 27, 1893. Serial No. 467,881. Term of patent 3½ years.

To all whom it may concern:

Be it known that I, LOUIS J. CHANDLER, a citizen of the United States, residing at Springfield, in the county of Hampden and State of Massachusetts, have invented and produced a new and original design for a badge to be used as a lapel ornament or other suitable form of decoration or insignia, of which the following is a specification, reference being had 5 to the accompanying drawing, forming part thereof, in which the figure is a representation in front face view of the badge.

The leading feature of my design consists in the delineation or configuration of a padlock and a roll or parchment, or paper, a portion of the latter being represented as behind the body of the padlock, while the other extremity of the roll protrudes through and beyond the opening between the body and bowed 10 neck or hasp of the padlock.

In the drawing, A is a representation of the padlock of which *a* is the body and *b* the bowed neck or hasp; and B represents the roll of parchment or paper; the extremity, *d*, of the roll is indicated as coming through and extended beyond the opening, *f*, and the convolutions of the sheet material are indicated at *n*. The plate bearing the badge is represented as of the outline of the configuration as composed of the representation of the padlock and roll. 25 30

What I claim is—

The design for a badge, substantially as shown and described.

LOUIS J. CHANDLER.
